[57] CLAIM

The ornamental design for an electronic tick remover, as shown and described.

DESCRIPTION

FIG. 1 is a perspective view of an electronic tick remover, showing my new design;
FIG. 2 is a top plan view thereof;
FIG. 3 is a front elevational view thereof;
FIG. 4 is a right side elevational view, the left side being a mirror image thereof;
FIG. 5 is a bottom plan view thereof; and,
FIG. 6 is a rear elevational view thereof.

*FIG. 1.**FIG. 2.**FIG. 3.**Fig. 4.**Fig. 5.**Fig. 6.*
